CONSTRUCTION OF WALLS, PARTITIONS,
AND THE LIKEMaurice Fould, Paris, France, assignor to Forges
de Strasbourg (Société Anonyme), Paris,
France, a company of FranceApplication June 20, 1939, Serial No. 280,157
In France May 27, 1939

7 Claims. (Cl. 189—34)

The present invention relates to systems for the quick construction of walls, partitions and the like by assembly of standard elements.

It has already been proposed to construct such walls by means of panels which each have a male edge and a female edge and fit into each other consecutively. However, the manufacture of such panels, which are usually made of metal, was somewhat complicated and comparatively costly in view of the shape of the female edge the formation of which required several operations in the case of sheet metal panels.

The chief object of the present invention is to provide a construction system of the type above mentioned which avoids this drawback.

According to an essential feature of the present invention, the two assembling edges of each panel are both male rounded edges, and the panels are connected to one another by means of elements each provided on its assembling edges with recesses opening into said edges through slots adapted for the hinge-like engagement of said panel edges in said recesses, the inner walls of said recesses being so shaped as to cooperate with said panel edges for guiding and positioning them.

It is thus possible to manufacture the panels themselves either by rolling, or in a press, the interconnecting elements being obtained for example with a cutter-wheel, starting either from sheet or strip metal. Furthermore, for a wall of given strength, the assembling elements can be made of smaller thickness than that of the panels since their cross-section has a very favorable moment of inertia, so that the cost of manufacture of the wall is substantially reduced both owing to the reduction of the weight of matter and to the simplification of manufacture.

In order to make the assembling elements perform the function of a framework or frame for the wall, I may, according to an embodiment of my invention, construct the assembling elements provided with the female joints in the shape of posts, for example like a box-girder; for this same purpose, I may make the assembling elements thicker than the panels themselves.

Other features of the present invention will be apparent from the following detailed description of some specific embodiment thereof.

Preferred embodiments of the present invention will be hereinafter described, with reference to the accompanying drawings, given merely by way of example, and in which:

Fig. 1 shows a section of the assembly of two panels.

Figs. 2 and 3 show box-shaped assembling elements.

Figs. 4 and 5 are partial views of a wall with a transverse partition.

Figs. 6 to 18 show sections of various embodiments of the assembling elements.

Fig. 19 shows a section of an embodiment of a wall.

Fig. 20 is a section of an element for assembling parallel rows of panels.

As shown in particular in Figs. 5 and 19, the metal panels 1 are each provided with two parallel male engaging edges 2; the assembling of two consecutive panels 1 to each other is effected by means of a separate element 3, the simplest shape of which is shown in Fig. 1 and which is provided with two parallel female engaging edges 4.

The cooperating edges of each panel and the corresponding interconnecting element are made as disclosed in my prior U. S. patent application Ser. No. 63,952, filed Feb. 14, 1936, now U. S. Patent No. 2,164,681 issued July 4, 1939. For instance, as shown by Fig. 1, the interconnecting element includes a central portion 3 extending to a short distance from each edge of the element, and bent so as to form two substantially semi-circular wings, extending each from the central part of said portion to a point slightly beyond the bent edge thereof, said wings located behind central portion 3 having their concavity turned toward said portion. The male engagement edge 2 of each panel 1 is rounded so as to fit in the recess thus formed on either side of the middle place of the interconnecting element, along the inner wall of said recess. Each panel can thus be engaged with the adjacent interconnecting element by sliding in the direction of the rounded edge thereof, or, preferably, by inserting the edge of the panel in the slot existing between the edge of central portion 3 and the outer edge of wing 4, and then pivoting the panel about an axis parallel to said edge, with a hinge-like assembly, until the outer edges of parts 2 and 4 substantially abut the body portions of parts 3 and 1 respectively.

In the case of Fig. 1, the element 3 serves no other purpose, in addition to that which consists in keeping two panels 1 assembled, than to provide the continuity of the outer surface of the wall obtained. In all the other figures, the element 3 is so constructed as to perform in addition the function of a frame or framework element and optionally of an element for assembling to another wall which extends in a different di-

rection, for instance perpendicular to the first. Finally, the assembling element may be used as a spacing and fixing element for a wall which extends parallel with the row of panels, in order to form, for example, an insulating wall.

According to Figs. 2 and 4, it is a box-shaped framework element 5 which acts as a connecting member between two consecutive panels 1. The wall 6 of said element opposite the wall forming the assembling edges is of U-shaped cross-section in order to enable the end of a perpendicular partition 7 to be fitted therein.

On the other hand, the corresponding face 8 of the element shown in Fig. 3 is plane, in order to enable any wall 8 that may form an insulating wall with the wall 1, to be fixed parallel with the row of panels 1 (Fig. 19).

Figs. 6 to 9 show that the element 5 may be of any desired cross-section and in particular be provided, on the face on which are formed the female assembling joints 4, with a projecting medial part 9 forming an ornamental rib of any cross-sectional shape.

Figs. 10 to 18 show various embodiments of an assembling element 3 similar to that of Fig. 1, but slightly wider so as to enable a framework element of any shape, made of folded sheet metal 10 (Figs. 10, 11, 12, 17 and 18), of section iron 11 (Figs. 13, 14 and 16) or even of wood or any other material 12 (Fig. 15), to be added between the female joints 4. In Figs. 17 and 18, the element 3 is so shaped as to form an ornamental rib 13. As shown in Fig. 5, the element 3 and the framework 10 which is associated therewith enable on the one hand a wall 7 perpendicular to the row of panels 1 to be fitted into the concave face 14, and on the other hand a wall 8 parallel with the row of panels 1 to be fitted between the flanges 15 and 16.

Finally, Fig. 20 shows a box-shaped assembling element 5 intended for constructing a wall or other partition having two parallel rows of panels 1. The element 5, which in this case is symmetrical with respect to the medial plane of the wall, acts at the same time as an element for assembling the panels 1 in two rows, as a bracing and spacing element for said two rows and finally as a framework or frame element.

While I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

I claim:

1. A system for the construction of walls, partitions, and the like, which comprises, in combination, flat panels having each two opposed parallel assembling edges of curvilinear bent shape, and interconnecting posts having each a central front portion extending over the whole width of said post, two curvilinear wings of a shape corresponding to that of said panel assembling edges, having their concavities turned toward said central front portion and extending, at the rear of said central front portion from an intermediate point thereof to a short distance beyond the lateral edge thereof so as to form in said post a narrow vertical slot for the engagement of the rounded edge of the corresponding adjoining panel, and a box like structure rigid with said central front portion for stiffening said post

against efforts perpendicular to the said panels.

2. A system for the construction of walls, partitions and the like, which comprises, in combination, flat panels having each two opposed parallel assembling edges of curvilinear bent shape, and interconnecting posts having each a central front portion extending over the whole width of said post, two curvilinear wings of a shape corresponding to that of said panel assembling edges, having their concavities turned toward said central front portion and extending at the rear of said central front portion from an intermediate point thereof to a short distance beyond the lateral edge thereof so as to form in said post a narrow vertical slot for the engagement of the rounded edge of the corresponding adjoining panel, and a structural shape rigid with said central front portion in such manner as to stiffen said post against efforts perpendicular to said panels.

3. A system for the construction of walls, partitions, or like building structures, which comprises, in combination, a plurality of substantially rectangular panels of sheet material, each being provided along opposite parallel edges with arcuate flanges curved away from the general plane of the panel, panel interconnecting and supporting elements interposed between adjacent edges of adjacent panels, said elements being formed of sheet material and being substantially co-planar with the panels, the opposite parallel edges of said elements being bent to provide folded portions which form of themselves channel-like recesses along said edges, said recesses being partly closed so that a narrow slot-like aperture is formed, said aperture being of a width approximating the thickness of the material of the flanges of said panels and having an internal arcuate wall surface of the same curvature as said flanges, for the guiding and positioning of the latter, the folded edge portions of said elements providing the rigidifying and stiffening means for said elements.

4. A system for the construction of walls, partitions or the like, which comprises, in combination, a plurality of substantially rectangular panels of sheet material, each being provided with opposed parallel edges curved away from the general plane of the panel substantially in the form of portions of circular cylinders, panel-interconnecting elements interposed between adjacent edges of adjacent panels, each of said elements having a central body portion of a width slightly less than the total width of said element and curved wings formed along each edge of said element, said wings extending in opposite directions from points spaced inwardly from the lateral edges of said body portion and on the rear side thereof, said wings being substantially cylindrically concave and projecting a short distance beyond the said edges of said body portion, the concavity facing toward the plane of said body portion, whereby there is provided a pocket along each edge of the interconnecting elements having a narrowed slot-like aperture and an inner wall surface of the same contour as that of said panel edges for the guiding and positioning of said panel edges.

5. A system for the construction of walls, partitions or the like, which comprises, in combination, a plurality of substantially rectangular panels of sheet material, each being provided with opposed parallel edges curved away from the general plane of the panel substantially in the form of portions of circular cylinders, panel-

interconnecting elements interposed between adjacent edges of adjacent panels, each of said elements having a central body portion of a width slightly less than the total width of said element and curved wings formed along each edge of said element, said wings extending in opposite directions from points spaced inwardly from the lateral edges of said body portion and on the rear side thereof, said wings being substantially cylindrically concave and projecting a short distance beyond the said edges of said body portion, the concavity facing toward the plane of said body portion, whereby there is provided a pocket along each edge of the interconnecting elements having a narrowed slot-like aperture and an inner wall surface of the same contour as that of said panel edges for the guiding and positioning of said panel edges, and a box-like structure rigidly secured to the laterally outward edges of said wings, to form with said interconnecting element a rigid post for supporting and reinforcing said panels.

6. In a system for the construction of paneled walls, partitions or the like, a post element for supporting and reinforcing such constructions and interconnecting the panels thereof, said post element being of a box-like structure, basically rectangular in cross-section and provided at intermediate points on each of a pair of its opposite sides with oppositely extending wings for interlocking with curved flanges provided on adjacent edges of adjacent panels which are to be interconnected, said wings each comprising a flange portion extending substantially perpendicularly to the side of the post and a substantially cylindrically concave portion disposed rearwardly of said flange portion with the concavity facing toward the plane of the latter and extending slightly beyond the edge of said flange por-

tion, whereby there is provided a pocket having a narrowed slot-like aperture and an inner wall surface of the same contour as that of said panel edges for the guiding and positioning of said panel edges.

5. A system for the construction of walls, partitions or the like, which comprises, in combination, a plurality of substantially rectangular panels of sheet material, each being provided with opposed parallel edges curved away from the general plane of the panel substantially in the form of portions of circular cylinders, panel-interconnecting elements interposed between adjacent edges of adjacent panels, each of said elements having a central body portion of a width slightly less than the total width of said element and curved wings formed along each edge of said element, said wings extending in opposite directions from points spaced inwardly from the lateral edges of said body portion and on the rear side thereof, said wings being substantially cylindrically concave and projecting a short distance beyond the said edges of said body portion, the concavity facing toward the plane of said body portion, whereby there is provided a pocket along each edge of the interconnecting elements, having a narrowed slot-like aperture and an inner wall surface of the same contour as that of said panel edges for the guiding and positioning of said panel edges, certain of said interconnecting elements being each incorporated into a hollow box-like post structure substantially rectangular in cross-section, in which said element comprises one side, and the opposite side is constituted by a similar element which serves to interconnect adjacent panels of a wall structure, in order to provide a double wall.

MAURICE FOULD.
